United States Patent Office

Des. 186,384
Patented Oct. 20, 1959

186,384

DESK OR THE LIKE

David Chapman, Chicago, Ill., assignor to The Brunswick-Balke-Collender Company, Chicago, Ill., a corporation of Delaware

Application April 29, 1959, Serial No. 55,691

Term of patent 14 years

(Cl. D33—11)

Fig. 1 is a perspective view of a desk or the like, showing my new design looking diagonally at the rear thereof;

Fig. 2 is a rear elevational view of the desk or the like;

Fig. 3 is a side elevational view of my desk or the like looking toward the right in Fig. 2;

Fig. 4 is a front elevational view thereof; and

Fig. 5 is a vertical section taken generally along the line 5—5 in Fig. 2.

The dominant features of my design are shown in full lines.

I claim:

The ornamental design for a desk or the like, as shown and described.
